SAND DRYING APPARATUS

Allan Maurice Cowburn, Islington, New South Wales, Australia

Application March 19, 1948, Serial No. 15,887
In Australia March 24, 1947

5 Claims. (Cl. 34—171)

1

This invention relates to apparatus for use in drying sand for use in the manufacture of glass, in forming cores for use in foundries, in copper-smithing and such other industries in which moisture in the sand is harmful or undesirable. It is applicable to the vertical type of sand drying apparatus in which the sand in its moist state is fed in at the top and gravitates past heated elements in its course to the point of discharge.

In apparatus of this type already in use, a container is provided, having a central cone with a flue at its apex, the sand being on the upper surface of the cone, which is heated from below. An outer casing of gauze or perforated metal allows the dried sand to escape.

This arrangement allows the sand to form a crust and to consolidate into a mass through which the steam generated by the contact of the damp sand with the heated cone, must pass. This causes a retardation of the drying of the balance of the sand.

The escape of the heated air and/or gases through the flue before the maximum heat has been extracted from them combined with the slowness of drying makes this process both inefficient in output and costly of operation.

It is the object of this invention to overcome these defects by providing an apparatus in which the sand is caused to pass successively over heated cones which first narrow and then enlarge so that the sand is not permitted to form a crust or consolidate in regular masses. Steam is thus readily liberated and escapes without appreciably retarding the drying of the balance of the sand.

The heated air and/or gases are not conveyed directly away by the flue but by means of escape vents or orifices from the major heating cone are directed to other parts of the drier where they combine with the steam from the sand in heating other cone surfaces until as much heat as possible has been extracted consistent with the desired speed of drying being maintained and the steam being released at a temperature high enough to prevent its condensation in undesirable quantities. It will be appreciated that whereas with moist sand a greater degree of heat may be extracted with less steam formation, where wet sand is being treated a very considerable degree of steam formation and condensation is likely. This may be minimised by providing special means such as drainage trays to deal with the condensate. In a modification the steam and fumes may be exhausted by mechanical means, but in this instance the degree of heat extraction will be diminished.

This invention is applicable to cones heated by electric elements or gas burners and in a modified form by the use of coke or oil fired furnaces, or other types of fuel, the gases from which are conducted by flues to the base of the main cone and

2

by a baffle arrangement against and along the surfaces they are designed to heat. Where the sand dryer is located adjacent to a source of heat, such as an annealing furnace, core stove or the like, a flue pipe carrying waste flue gases may be introduced under the main cone as in the form described for coke burning. Adjustable means are provided for the escape of the dried sand and for separation of foreign matter.

When treating sand which has not a great deal of moisture content with the cones heated by oil, gas or electricity, it is found that particles of sand in direct contact, either with the interior cone formations or with the vents from which the heated gases issue, become dried before they approach the point of discharge. In such circumstances I provide a number of perforations in the cones and/or vents and allow the dried sand to fall direct to the collecting means. This permits other particles to have direct contact with the heated cones and vents and accelerates the speed of operation.

In order to describe the invention more fully, reference will now be made to the drawings accompanying and forming part of this complete specification and where:

Fig. 1 is a partly sectional elevation of a sand dryer suited for heating by a gas burner.

Fig. 2 is a vertical section of the unit taken on the line 2—2 of Fig. 3.

Fig. 3 is an enlarged horizontal section on the line 3—3 of Fig. 2.

Fig. 4 shows an elevation of the sand dryer adapted for heating from a coke or oil burning unit, or waste flue gases.

Fig. 5 shows a suitable baffle arrangement for converting from a direct heating unit to a unit suitable for indirect heating as by waste flue gas, coke, oil or the like.

The sand drier consists of an open ended cylindrical container or casing 3, supported upon legs 4, having their upper ends inset and welded to plates 5, affixed to the container side wall by screws or the like. The lower ends of the legs 4, have feet 6, thereon and are connected by angular braces 7, and horizontal bar 8.

A screen 9, is fitted across the mouth of the container 3, above a hopper 10. The hopper 10, is of metal of inverted frusto-conical form, open at both ends, the lower or smaller end having positioned within it cone 11, which is attached to the top of a hollow frusto-conical primary sand-drier 12 axially aligned with the hopper 10.

The cone or primary sand drier 12 is retained in position by the cone supports 13 or equivalent supporting means. The supports 13 as shown are vertical sheets of metal affixed to the inner wall of casing 13 and the upper surface of cone 12. Escape vents 14, having welded to them a circular baffle plate 15 which may be described as a

sand flow retarding baffle ring, project from cone 12. The lower edge of baffle ring 15 is spaced from the surface of cone 15. A regulating band or annular shutter 16 is controlled by screw threaded studs 17 upstanding from the bottom of cone 12 and thereby fixed in relation to the container 3. The studs pass through orifices 18 in the lugs 19 that extend outwardly from the band 16. The band or shutter 16 may be manually adjusted by handles 26 and held in adjusted vertical position by the wing nuts on studs 17.

Heat is supplied in this form of the invention by gas burners 20 which in a preferred form are circularly arranged. The burners are supported by burner supports 21 attached to an inverted hollow frusto-conical secondary sand drier 22 which in turn is placed in fixed relation with the container 3 by supports 23 attached to legs 4. The secondary sand drier 22 being exposed to the open flame of burners 20 is also heated thereby. Sieve 24 is supported in frame 25.

In the coke fired model as illustrated in Fig. 4, the gas burners 20 and supports 21 are removed and in their place is inserted the baffle arrangement illustrated in Fig. 5.

The coke burner 27 is connected by flue 28 to the space 29 which is surmounted by the circular baffle 30 carried on supports 31.

Steam and fume escape holes 32 are in this form of the invention covered by flues 33.

In the form illustrated in Fig. 1, perforations, not shown, may be made in the cone 12 and/or the hollow projecting vents 14.

In operation, the sand to be dried enters the hopper 10 through the screen 9 which removes coarse foreign matter. Its flow is restricted and confined through the annular space 35 between hopper 10 and the conical apex 11. It then passes over the upper surface of primary drier 12, the thickness of the sand diminishing as the circumference of the cone increases, so that if the sand coming through the annular space 35 is two inches in thickness, it has diminished to about 1 1/4 inches by the time it has passed under the baffle ring 15 and to about 3/4 inch as it slides down the balance of the outer surface of the cone 12, past the annular baffle band 40, to the space 36 inside the annular discharge regulating band or shutter whence it falls through the controlled space between the shutter 16 and the primary drier 12 into the inverted lower secondary drier 22 and so through the sieve 24 where finer particles of foreign matter are removed.

Heat is applied in Fig. 1 by means of a circular gas burner 20 which heats the underside of the primary drier 12 and its apex 11 as well as the secondary drier 22. The hot air and fumes escape from primary drier 12 by the hollow projection vents 14 but are trapped in the space 37 where they mingle with the steam from the sand and assist to heat the underside of the hopper 10. When the requisite degree of heat has been extracted from the gases, they are allowed to escape by the escape holes 32. Smaller escape holes 39 are provided at a higher location to permit the escape of steam before it has condensed.

Steam escape holes 41 are also provided below baffle 40 to prevent condensation of steam generated in the lower portion of the container 3, while holes 42 permit escape of steam and sand.

In the form illustrated in Fig. 4 steam escape holes 39 are eliminated, as the steam and fumes are withdrawn by duct or mechanical means.

The discharge regulating band 16 may be man-

ually raised to release foreign matter from the interior of the drier.

Although in this specification the invention has been described as for the purpose of drying sand, it is also applicable to certain types of granulated materials such as metal chippings, filings, stone dust and the like.

I claim:

1. Gravity-fed sand-drying apparatus comprising an inverted frusto-conical feed hopper open at both ends, a hollow conical primary sand-drier mounted axially beneath said hopper and having the apex projecting through the open base of the hopper to form an annular feed opening for gravitational flow of sand from the hopper onto the external conical drying surface of said primary drier, annular baffles outstanding from the external surface of said primary drier and positioned in spaced relation between the annular feed opening and the base of said primary drier for impeding the gravitational flow of sand upon the external drying surface of said primary drier, an inverted hollow frusto-conical secondary sand-drier mounted axially beneath the primary sand-drier so as to receive sand from said primary drier, shutter means at the base of the primary drier for regulating gravitational transfer of the sand from the primary drier to the secondary drier, a sand discharge opening at the lower end of said secondary drier, and means for heating the drying surfaces of said primary and secondary driers.

2. Gravity-fed sand-drying apparatus comprising an inverted frusto-conical feed hopper open at both ends, a hollow conical primary sand-drier mounted axially beneath said hopper and having the apex projecting through the lower open end of the hopper to form an annular feed opening for gravitational flow of sand from the hopper onto the external conical drying surface of the primary drier, a sand-flow retarding baffle ring fixed with respect to and vertically upstanding and spaced from the external conical surface of the primary drier to form a restricted clearance therebetween and positioned in the vicinity of said annular feed opening and between said annular feed opening and the base of the primary drier, a sand-flow retarding annular baffle band arranged angularly from the external conical surface of the primary drier to form a restricted clearance between said external conical surface and the adjacent edge of the baffle band and located between said baffle ring and the base of the primary drier, an inverted hollow frusto conical secondary sand-drier mounted axially beneath and adjacent the hollow conical primary drier said secondary drier having an axial discharge opening and the inverted base diameter exceeding the base diameter of the primary drier, a vertically-adjustable annular shutter upstanding from and surrounding the base of the hollow conical primary drier for regulating gravitational transfer of the sand from the base of the primary conical drier to the secondary drier, and means for heating the primary and secondary driers.

3. Gravity-fed sand-drying apparatus comprising an inverted frusto-conical feed hopper open at the lower end and having a screening sieve at the upper end thereof, a hollow conical primary sand-drier mounted axially beneath said hopper and having the apex projecting through the lower open end of the hopper to form an annular feed opening for gravitational flow of sand from the hopper onto the external conical drying

surface of the primary drier, a sand-flow retarding baffle ring fixed with respect to and vertically upstanding and spaced from the external conical surface of the primary drier to form a restricted clearance therebetween and positioned in the vicinity of said annular feed opening and between said annular feed opening and the base of the primary drier, a sand-flow retarding annular baffle band arranged angularly from the external conical surface of the primary drier to form a restricted clearance between said external conical surface and the adjacent edge of the baffle band and located between said baffle ring and the base of the primary drier, an inverted hollow frusto-conical secondary sand-drier mounted axially beneath and adjacent the hollow conical primary drier said secondary drier having an axial discharge opening and the inverted base diameter exceeding the base diameter of the primary drier, a vertically-adjustable annular shutter upstanding from and surrounding the base of the hollow conical primary drier for regulating gravitational transfer of the sand from the base of the primary conical drier to the secondary drier, a screening sieve at the discharge opening of the secondary drier, and heating means positioned in the space between the hollow conical primary drier and the inverted hollow frusto-conical secondary drier for heating said driers.

4. Gravity-fed sand-drying apparatus comprising an inverted frusto-conical feed hopper open at the lower end and having a screening sieve at the upper end thereof, a hollow-conical primary sand-drier mounted axially beneath said hopper and having the apex projecting through the lower open end of the hopper to form an annular feed opening for gravitational flow of sand from the hopper onto the external conical drying surface of the primary drier, a sand-flow retarding baffle ring fixed with respect to and vertically upstanding and spaced from the external conical surface of the primary drier to form a restricted clearance therebetween and positioned in the vicinity of said annular feed opening and between said annular feed opening and the base of the primary drier, a sand-flow retarding annular baffle band arranged angularly from the external conical surface of the primary drier to form a restricted clearance between said external conical surface and the adjacent edge of the baffle band and located between said baffle ring and the base of the primary drier, an inverted hollow frusto-conical secondary sand-drier mounted axially beneath and adjacent the hollow conical primary drier said secondary drier having an axial discharge opening and the inverted base diameter exceeding the base diameter of the primary drier, a vertically-adjustable annular shutter upstanding from and surrounding the base of said hollow conical primary drier for regulating gravitational transfer of the sand from the base of the primary conical drier to the secondary drier, a casing forming a hot-gas chamber around the hopper and the primary drier by surrounding said hopper and primary drier from the top of the hopper to adjacent the top of the vertically-adjustable shutter and vented at the upper portion for escape of spent gas, a screening sieve at the discharge opening of the secondary drier, means positioned in the space between the hollow conical primary drier and the inverted hollow frusto-conical secondary drier for releasing hot gases therein to heat said driers, and a plurality of hot-gas flues passing through the wall of said hollow conical primary drier and extending from the hollow conical interior thereof into said hot gas chamber and in the vicinity of the under surface of said hopper for directing hot-gases against said hopper.

gas chamber and in the vicinity of said hopper.

5. Gravity-fed sand-drying apparatus comprising an inverted frusto-conical feed hopper open at the lower end and having a screening sieve at the upper end thereof, a hollow conical primary sand-drier mounted axially beneath said hopper and having the apex projecting through the lower open end of the hopper to form an annular feed opening for gravitational flow of sand from the hopper onto the external conical drying surface of the primary drier, a sand-flow retarding baffle ring fixed with respect to and vertically upstanding and spaced from the external conical surface of the primary drier to form a restricted clearance therebetween and positioned in the vicinity of said annular feed opening and between said annular feed opening and the base of the primary drier, a sand-flow retarding annular baffle band arranged angularly from the external conical surface of the primary drier to form a restricted clearance between said external conical surface and the adjacent edge of the baffle band and located between said baffle ring and the base of the primary drier, an inverted hollow frusto-conical secondary sand-drier mounted axially beneath and adjacent the hollow conical primary drier said secondary drier having an axial discharge opening and the inverted base diameter exceeding the base diameter of the primary drier, a vertically-adjustable annular shutter upstanding from and surrounding the base of said hollow conical primary drier for regulating gravitational transfer of the sand from the base of the primary conical drier to the secondary drier, a casing forming an annular hot-gas chamber around the hopper and the primary drier by surrounding said hopper and primary drier from the top of the hopper to adjacent the top of the vertically-adjustable shutter and vented at the upper portion for escape of spent gas, a screening sieve at the discharge opening of the secondary drier, means positioned in the space between the hollow conical primary drier and the inverted hollow frusto-conical secondary drier for releasing hot gases therein to heat said driers, and a plurality of hot-gas flues passing through the wall of said hollow conical primary drier and extending from the hollow conical interior thereof into said hot gas chamber and in the vicinity of the under surface of said hopper for directing hot-gases against said hopper.
